US00D981736S

(12) United States Design Patent (10) Patent No.: US D981,736 S
Sonnenschein (45) Date of Patent: * Mar. 28, 2023

(54) FABRIC WITH PATTERN

- (71) Applicant: Airwair International Limited, Northamptonshire (GB)
- (72) Inventor: Robin Sonnenschein, Northamptonshire (GB)
- (73) Assignee: AIRWAIR INTERNATIONAL LTD., Northamptonshire (GB)
- () Term: 15 Years
- (21) Appl. No.: 29/727,518
- (22) Filed: Mar. 11, 2020

(30) Foreign Application Priority Data

- Feb. 12, 2020 (EM) 007692728-0001
- (51) LOC (14) Cl. 05-05
- (52) U.S. Cl.
USPC D5/5
- (58) Field of Classification Search
